UNITED STATES PATENT OFFICE.

VICTOR H. FAIRLESS, OF TRENTON, TENNESSEE.

COTTON AND PEA PICKER SACK.

1,427,728.

Specification of Letters Patent. Patented Aug. 29, 1922.

Application filed May 26, 1921. Serial No. 472,702.

To all whom it may concern:

Be it known that I, VICTOR H. FAIRLESS, a citizen of the United States, residing at Trenton, in the county of Gibson, State of Tennessee, have invented certain new and useful Improvements in Cotton and Pea Picker Sacks; and I do hereby declare the following to be a full, clear, and exact description of the invention, such as will enable others skilled in the art to which it appertains to make and use the same.

My present invention relates to improvements in cotton or pea pickers' sacks, and it is intended to provide a cheap and durable sack, which may be readily connected to or removed from the supporting band, and which may be used in four different positions, as well as turned inside out, with the accompanying advantages, that will be hereinafter more fully described and claimed.

Such sacks as are now ordinarily manufactured are long enough to drag upon the ground when in use, with the result that sharp stones, the stubble of cotton or corn stalks, hard clods or the like tear or cut or rapidly wear out that portion of the sack which is dragged along the ground.

Moreover, when these sacks are turned end for end, as is sometimes done, the soiled portion of the sack which has been lately dragged upon the ground is brought next to the clothing of the operator, soiling the same.

These objections, and others, hereinafter referred to are in a large measure avoided by the use of the arrangement that will be hereinafter described.

My invention will be more clearly understood after reference to the accompanying drawings, in which like parts are indicated by similar reference symbols throughout the several views, and in which:

Figure 1 is a front elevation of the complete sack ready for use, parts being broken away;

Figure 2 shows a section along the line 2-2 of Figure 1 and looking in the direction of the arrows;

Figure 3 is a detail showing on a larger scale the metallic fastening means, by means of which the sack is detachably connected

to the supporting band over the shoulder of the picker, and

Figure 4 shows in full lines a section along the line 4-4 of Figure 3, with the supporting loop shown in dotted lines in the lower or detaching position.

A represents the main body of the sack, which is preferably made of two strips of cotton duck or the like, and sewed together at the sides as at a^0 , the whole forming a tubular body portion open at both ends. The opposite sides of the top and bottom of the sack are slit a distance from the ends to form four flaps a^1 , a^2 , a^3 , and a^4 , and four intermediate tabs a^5 , a^6 , a^7 and a^8 . These flaps are turned over at their ends to form reinforcements B, and these reinforced portions are provided with eyelets b. The side edges of the flaps are also reinforced by means of heavy folded over taped edges B^1 (see Fig. 1), which reinforces preferably project beyond the free ends a of said flaps. These reinforces B^1 are also provided with eyelets b similar to those already described. The tabs preferably include the doubled up edges of the seams a^0 and are further reinforced by suitable reinforcing tape or the like B^2 , which is also provided with eyelets, the said eyelets being adapted to receive suitable lacings such as C and C^1 , as will be hereinafter more fully described.

The free end of each tab is bent over as at a^{10} to engage in the slot d^0 of the plate D, which serves as the lower member of a buckle or fastener by which the sack is suspended from the shoulder band F.

The upper member of this buckle or fastener E comprises a toggle having arms e connected by the stem e^1 to the loop e^2 , this loop engaging the free ends f of the band F, as shown in Fig. 1.

The toggle arms e are adapted to fit snugly under the curved hooks d of the plate D as shown clearly in Figs. 3 and 4, and when the sack is in use in the position shown in Fig. 1, there will be no tendency of the fastening means to become disengaged, but in order to release the sack from the supporting band, it will only be necessary to turn the member E down from the position shown in full lines in Fig. 4 to the position

shown in dotted lines in Fig. 4, and the two parts D and E may be quickly and conveniently disengaged.

In assembling the parts for use, the bottom flaps a^3 and a^4 are secured together with lacings C¹, and the sack is then turned inside out with the lower tabs and plates on the inside, thus providing a smooth even surface on the exterior of the bottom of the sack, which is not likely to catch in stubble or stones, cotton stalks or the like. The bottom of the sack being closed, one of the upper flaps as a^2 is laced to the adjacent side of the tabs by means of lacings C, as shown in Fig. 1, and the other flap a^1 is allowed to hang down, the plates D are now connected to the toggles E, and the parts are in position shown in Fig. 1. In such position, the rear flap is next to the body of the wearer and serves as an apron to prevent any of the cotton or peas picked from falling in the space between the sack and the clothing of the wearer. Moreover, this apron protects the clothing of the wearer.

At the same time the loose flap a^1 hangs down in front and by its weight tends to pull open the front of the sack, leaving a clear space into which the picker can conveniently drop the cotton or peas or other articles, as he picks the same.

When desired, the sack may be turned 180° about its vertical axis by simply lacing the flap a^1 to the tabs a^5 and a^6 and unlacing the flap a^2 and allowing it to drop down. The fastening plates D will remain in the same position, making it unnecessary to shift from one toggle to the other, and what has been the front of the sack will now be the rear and vice versa.

In order to shift the sack end for end, unlace the bottom lacing C¹, opening the bottom end of the sack, remove the toggles E, lace the side edges of the loose front flap a^1 , then lace the two upper edges of the flaps a^1 and a^2 together; and turn the sack inside out, like a bolster case, until the former closed bottom becomes the open top, and adjust the flaps a^3 and a^4 similarly to the flaps a^1 and a^2 as shown in Fig. 1. What was once the bottom of the sack now becomes the top, and what was formerly the inside of the sack now becomes the outside.

Thus a relatively clean surface is exposed at the rear of the top of the sack where it forms an apron next to the clothing of the user. However, if the user so desires it is possible to conveniently reverse the ends of the sack, permanently changing the inside to the outside.

The sack so reversed endwise may now be shifted through 180°, as before described. Thus, it will be seen that the sack may be used in four different positions, presenting four faces near the bottom to be separately subjected to wear; and thus, the life of the

sack may be increased substantially four fold over a sack which is intended to be worn on one face only.

It will be noted that the bottom portion of the sack when in use and partly filled with cotton or the like will be lenticular in cross section, and will tend to drag along the ground without rolling over, as is found with those sacks having their bottoms drawn together with a puckering string arrangement.

Moreover, with the herein described construction quite a large surface of the sack will drag over the ground diminishing local wear.

It will be noted that whichever end of the sack is uppermost the lacing, hook plates, and rough edges of the lower end will be turned inwards leaving a smooth surface at the bottom which is not likely to catch in any object projecting from the ground; while at the same time a tight closure is secured at the bottom, by means of an over-seam lacing.

It will be noted that the sack will be of the same operative length whichever end is used as the top or bottom.

By having the supporting tabs made integral with the main body of the sack and reinforced as shown, they are less likely to tear loose or break away than when sewn or otherwise attached to the sack.

Any suitable shoulder band or strap may be used, preferably adjustable; and the herein described fastening device affords a quick and convenient mode of connecting the sack to the shoulder strap, or separating the two, as required.

It will be seen that the complete apparatus is very cheap and simple in construction, and durable and effective in use.

It will be obvious that various changes might be made in the construction and arrangement of the herein described parts, which could be used without departing from the spirit of my invention, and I do not mean to limit the invention to such details, except as particularly pointed out in the claims.

Having thus described my invention, what I claim and desire to secure by Letters Patent of the United States is:

1. In a harvester's equipment the combination with a four way sack comprising a body portion in the form of a tube provided at each end with a pair of oppositely disposed flaps, with a pair of oppositely disposed tabs provided between each pair of flaps, said flaps and tabs being provided with eyelets adapted to receive lacings of a shoulder strap, and fastening means for detachably connecting said tabs to said shoulder strap, substantially as and for the purposes described.

2. In a harvester's equipment the combination with a four way sack comprising a body portion in the form of a tube provided at each end with a pair of oppositely disposed flaps, with a pair of oppositely disposed tabs provided between each pair of flaps, said flaps and tabs being provided with eyelets adapted to receive lacings of a shoulder strap, and fastening means for detachably connecting said tabs to said shoulder strap, substantially as and for the purposes described.

nation with a four way sack comprising a body portion in the form of a tube provided at each end with a pair of oppositely disposed flaps, with a pair of oppositely disposed tabs provided between each pair of flaps, and also integral with the body portion of the sack, said flaps and tabs be-

ing reinforced and provided with eyelets adapted to receive lacings, of a shoulder strap, and fastening means for detachably connecting said tabs to said shoulder strap, substantially as and for the purposes described.

VICTOR H. FAIRLESS.
